UNITED STATES PATENT OFFICE.

WILLIAM P. WELD, OF MARIANNA, ARKANSAS.

GIN-ROLL BOARD AND FEEDER.

No. 834,176.

Specification of Letters Patent.

Patented Oct. 28, 1906.

Application filed June 29, 1906. Serial No. 324,084.

To all whom it may concern:

Be it known that I, WILLIAM P. WELD, a citizen of the United States, residing at Marianna, in the county of Lee and State of Arkansas, have invented a new and useful 5 Gin-Roll Board and Feeder, of which the following is a specification.

This invention relates to feed-regulators for gins; and its object is to provide a device 10 of this character having means for controlling the rotation of the feed-wheel in proportion to the size of the cotton roll within the gin.

A still further object is to provide a roll-board which is movably connected to the gin and is adapted to regulate the positions 15 of the feed-pawls.

Another object is to provide a roll-board having means whereby the cotton roll is 20 visible at all times, thereby permitting the scorching of the cotton, &c., to be easily detected.

A further object is to provide a roll-board which can be quickly detached, so as to enable 25 the entire cotton roll to be removed from the gin, if desired.

With the above and other objects in view the invention consists of a guide on which are 30 mounted slides having a spring-pressed arm mounted therein. This arm extends from the roll-board and supports it in proper position. The pawls of the feed mechanism have sliding fulcrums and are connected to opposite ends of a centrally-fulcrumed lever, 35 which is in turn connected to the roll-board and adapted to be actuated thereby. The movement of the roll-board will cause the shifting of the fulcrums of the pawls and increase or diminish the strokes thereof and 40 correspondingly affect the rotation of the feed-cylinder.

The invention also consists in providing means whereby the slides may be quickly removed from the guide, so as to permit the 45 entire cotton roll to be dumped, if desired.

The invention further consists in providing a glass strip within the roll-board, so that the roll will be visible at all times to the operator, who can therefore readily detect the 50 scorching of the cotton, &c.

The invention also consists of certain other novel features of construction and combinations of parts, which will be hereinafter more fully described, and pointed out in the claims.

55 In the accompanying drawing is shown the preferred form of the invention.

Said drawing is a perspective view of a portion of a gin and showing the invention applied thereto.

Referring to the drawing, 1 is a gin having 60 a roll-board 2 disposed in front of the roll-box 3, and in the roll-board is disposed a strip of glass 4, whereby the cotton roll is rendered visible at all times to the operator. Extending from the roll-board is an arm 6, 65 which is slidably mounted within a block 7, mounted upon and engaging a channeled guide 8, which is arranged on the gin. This guide is formed with teeth 9, adapted to be engaged by a pawl 10 upon the block. An- 70 other block 11 is slidably mounted on the guide 8 and has a threaded opening 12 therethrough, into which is screwed the threaded end 13 of the arm 6. A nut 14 is mounted on the threaded portion of the arm and is adapted to clamp a coiled spring 15 against the block 7.

A T-shaped lever 16 is centrally fulcrumed upon one side of the guide 8 and the depending arm, and this lever is connected by 80 means of a rod 17 with the forward end of arm 6. The gin is provided with the usual ratchet-wheel 18, which is connected to the feed-cylinder, (not shown,) and this ratchet-wheel is engaged by two pawls 19 and 20, the 85 pivot-pins 21 and 22 of which are mounted in slots 23, disposed longitudinally within a lever 24 at opposite sides of the fulcrum 25 thereof. This lever is adapted to be driven by a pitman 26, which is connected to one 90 end thereof and to a drive-shaft 27. The ends of the pawls 19 and 20 extend beyond the lever, and one end of the pawl 19 is secured to one end of lever 16 by means of a rod 26, while the other end of lever 16 is connected by a rod 27 to one end of the pawl 20. 95

In operation the cotton is fed into the roll-box 3 in any desired manner, this being caused by the rotation of the ratchet-wheel 17. Said wheel is rotated by the actuation 100 of lever 24 and the alternate engagement by the pawls with the lever. The spring 15 serves to hold the roll-board 2 normally in a predetermined relation with the box 3; but should the cotton roll become of too large proportions the roll-board will be pushed outward and will cause the arm 6 to slide longitudinally, thereby compressing the spring 15. This longitudinal movement of the arm will cause rod 17 to pull on the depending 105 arm of lever 16, and as a result the upper pawl 19 will be drawn toward the fulcrum 25,

while the lower pawl 20 will also be pushed toward said fulcrum. The strokes of these pawls will thus be materially diminished and the rotation of the ratchet will be correspondingly reduced. Should the outward movement of the roll-board continue, the lever 16 will pull further on the pawl 19, so that its fulcrum 21 will bear against the lower end of the upper slot 23, and said pawl will therefore be swung entirely out of engagement with the ratchet-wheel. The movement of said wheel will thus be practically stopped, because it will be actuated solely by the lower pawl, and the stroke of said pawl will be so short that in view of its proximity to fulcrum 25 it will practically leave the ratchet-wheel stationary. The supply of cotton to the roll-box will thus be practically cut off, and as the roll diminishes the spring 15 will return all of the parts to their normal positions and the rotation of the ratchet-wheel 17 will gradually increase. Should the cotton roll become scorched or should dents appear within the roll, the same can be readily detected through the glass 4, and, if desired, the entire roll can be removed by lifting the pawl 10 and withdrawing the two blocks 7 and 11 from the guide 12. It will of course be necessary to detach the rod 17 from lever 16.

The preferred form of the invention has been set forth in the foregoing description; but I do not limit myself thereto, as I am aware that modifications may be made therein without departing from the spirit or sacrificing the advantages thereof, and I therefore reserve the right to make such changes as fairly fall within the scope of the claims.

What is claimed is—

- 40 1. In a gin the combination with feed mechanism; comprising a ratchet-wheel and a pawl having a slidable fulcrum of a longitudinally movable arm, a roll-board carried thereby, and mechanism actuated by the roll-board for sliding the fulcrum of the pawl.
2. In a gin the combination with feed mechanism; comprising a ratchet-wheel and a pawl having a slidable fulcrum of a roll-board movably carried by the gin, and means operated by the roll-board for sliding the fulcrum of the pawl.
3. In a gin the combination with feed mechanism; comprising a ratchet-wheel and a pawl having a slidable fulcrum of a guide, a roll-board movably connected to the guide, and means operated by the roll-board for sliding the fulcrum of the pawl.
4. In a gin the combination with feed mechanism; of a guide, slides detachably mounted thereon, an arm within the slides, a roll-board movable with the arm, and means operated by the roll-board for controlling the feed mechanism.
5. In a gin the combination with feed mechanism; comprising a ratchet-wheel and

a pawl having a slidable fulcrum of a roll-board movably connected to the gin, a lever fulcrumed upon the gin, a rigid connection between the lever and roll-board, and means operated by the lever for sliding the fulcrum 70 of the pawl.

6. In a gin the combination with feed mechanism comprising a ratchet-wheel, a lever, and pawls fulcrumed upon the lever; of a roll-board movably connected to the gin, a 75 second lever, a rigid connection between said lever and the roll-board, and rigid connections between the second lever and the pawls.

7. In a gin the combination with a movable roll-board, a centrally-fulcrumed lever 80 having a depending portion, and a rigid connection between said depending portion and the roll-board; of a feed ratchet-wheel, a lever fulcrumed between its ends adjacent the ratchet-wheel, means for actuating the lever, 85 pawls having movable fulcrums upon the lever, and rigid connection between the pawls and the first-mentioned lever.

8. In a gin the combination with a movably-supported roll-board, a T-shaped lever, 90 and a connection between said lever and roll-board; of a longitudinally-slotted lever, a feed ratchet-wheel adjacent thereto, means for actuating the lever, pawls having fulcrums movably mounted within the slots, 95 and connections between said pawls and opposite portions of the T-shaped lever.

9. In a gin the combination with a guide; of slides detachably mounted thereon, an arm slidably mounted within one of said slides and engaging the other slide, a normally tensioned spring for exerting a constant longitudinal pressure upon the arm, a roll-board carried by the arm, an angular lever, a connection between said lever and the roll-board, a ratchet-wheel, mechanism for rotating said wheel, and means operated by the angular lever for controlling said rotation.

10. In a gin the combination of a feed 110 ratchet-wheel, a lever fulcrumed between its ends adjacent thereto, pawls fulcrumed upon and slidably connected to said lever, means for actuating the lever, and means operated by a cotton roll within the gin for sliding the 115 pawls in opposite directions to regulate the rotation of the ratchet.

11. In a gin the combination with a feed-ratchet, and alternately-operating pawls slidably mounted adjacent the ratchet; of a 120 roll-board, an arm extending therefrom and supporting the same, a guide, slides upon the guide and supporting the arm, mechanism operated by the roll-board for moving the fulcrums of the pawls from or toward each other simultaneously during their actuation, and means for detachably securing the slides and arm upon the guide.

12. In a gin the combination with a roll-board; of a feed ratchet-wheel, pawls hav- 130

ing movable fulcrums adjacent the ratchet-wheel, mechanism for alternately shifting the pawls into engagement with the ratchet-wheel, and means operated by the roll-board 5 for moving the fulcrums of the pawls from or toward each other during their actuation to regulate the rotation of the ratchet-wheel.

In testimony that I claim the foregoing as my own I have hereto affixed my signature in the presence of two witnesses.

WILLIAM P. WELD.
